UNITED STATES PATENT OFFICE.

HARRY W. McMULLIN, OF DENVER, COLORADO, ASSIGNOR TO THE McMULLIN AUTOMATIC TOP COMPANY, OF DENVER, COLORADO, A CORPORATION OF COLORADO.

MEANS FOR OPERATING AUTOMOBILE-TOPS.

1,323,537.

Specification of Letters Patent.

Patented Dec. 2, 1919.

Application filed October 18, 1917. Serial No. 197,335.

To all whom it may concern:

Be it known that I, HARRY W. McMULLIN, a citizen of the United States, residing at the city and county of Denver and State of Colorado, have invented certain new and useful Improvements in Means for Operating Automobile-Tops; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in means for operating the tops of automobiles, and relates more particularly to a construction adapted to quickly and automatically raise the top from its lowered or down position.

The advantage of a construction of this kind will be readily understood, since the time required to raise an automobile top under ordinary conditions and with the constructions generally heretofore in vogue, often results in those who are engaged in it being exposed to storms, as heavy rains particularly in mountainous regions where storms begin without much warning.

Another feature of the invention consists in the means for removing the boot or cover of the top from the latter when in the down position, said removal being automatic and preparatory to and practically simultaneous with the elevation of the top.

The raising of the top is accomplished by spring-actuated mechanism which is released by closing an electric circuit. The specific construction employed is an electromagnet of the solenoid type, the core of the solenoid when the coil is energized serving to move a rod with which it is connected sufficiently to actuate a pair of bell crank levers which serve through the medium of suitable connections, to operate parts whereby the latter are brought into position to be engaged by spring-actuated latches, the movement of the latches incident to the engagement of said parts serving to release the devices which hold the top in the down position against the tension of the springs which operate the means for raising the top.

Having briefly outlined my improvement I will proceed to describe the same in detail,

reference being made to the accompanying drawing in which is illustrated an embodiment thereof. In this drawing:

Figure 1 is a side elevation of an automobile body showing a top connected to be operated by my improvement.

Fig. 2 is a horizontal section taken through the body on a line 2—2, Fig. 1 looking downwardly.

Fig. 3 is a section taken on the line 3—3, Fig. 1, looking toward the right, the parts being shown on a larger scale.

Fig. 4 is a section taken on the line 4—4, Fig. 1 viewed in the direction indicated by the arrows, the parts also being shown on a larger scale.

Fig. 5 is a section taken on the line 5—5, Fig. 3 looking toward the left, the parts being shown on a larger scale.

Fig. 6 is a top plan view of the rear seat portion of the automobile showing the boot and its elastic strap connections extended preparatory to applying the same to the top after the latter is down.

Fig. 7 is a section taken on the line 7—7, Fig. 6, the parts being shown on a larger scale.

Fig. 8 is a fragmentary side view of the rear portion of the body of an automobile showing the top down and my improved boot applied. In this view, the operating mechanism is also illustrated.

The same reference characters indicate the same parts in all the views.

Let the numeral 5 designate the body of an automobile whose top 6 consists of long bows 7 and 8, a short bow 9, together with a system of levers 10 connected with the bows and with the cover 12, in such a manner as to extend the forward portion of the top and raise the rear bow 7 by the positive or direct operation of the bow 8. This lever system is substantially the same as illustrated in Patent No. 1,246,449 granted to me November 13, 1917, and therefore, need not be described in extreme detail, since nothing is claimed in this application on the specific construction of the top mechanism, and as any suitable system of lever connections which will perform the said function during the raising operation and at the same time allow the bows to fold into small compass, as illustrated in Fig. 8 of the drawing, will serve the purpose. Hence, the mechanism acting on the long bow 8 for the purpose of

raising the top will now be described. It should be stated, however, that the lower extremities of the side arms of the bow 7 are pivotally connected as shown at 13 with a projection 14 formed on the lower part of the bow 8.

The lower extremity of each arm 15 of the bow 8 is rigidly connected, as shown at 16, with one extremity of a crank arm 17 whose opposite extremity is pivotally connected as shown at 18 with a link 19, the opposite extremity of the link being pivotally connected as shown at 20 with a crank arm 21 whose opposite extremity is rigidly secured as shown at 22 with one extremity of a rock shaft 23. Between the extremities of the rock shaft, depending crank arms 24 are rigidly secured to the shaft at their upper extremities, their lower extremities being respectively pivotally connected as shown at 25 with the forward extremities of rods 26, as shown at 27, the rear extremities of the rods being secured as shown at 28 to the central portions of yokes 29 to whose opposite extremities are attached, as shown at 30 the rear ends of spiral springs 31 whose forward extremities are secured as shown at 32 to a stationary support 33 which is perforated or open to allow the rods 26 to pass freely therethrough. When the automobile top is lowered or in the down position, as shown in Figs. 3 and 8, the rock shaft 16 and its connections are operated to place the springs 31 under tension, as illustrated in Fig. 8. After the top has been lowered or moved to the position shown in the last named figure, the boot or flexible housing 34 (see Fig. 6), is drawn out of a pocket 35 in the body of the machine in the rear of the seat as indicated by the forward dotted line in Figs. 1 and 8. In Fig. 1 the collapsed boot 34 is indicated by dotted lines within the pocket 35. This boot is composed of flexible material preferably water proof, but not in itself elastic, and as illustrated in the drawing, referring to Fig. 6, may be said to be composed of parts 36, 37, 38 and 39. To the boot is secured at points 40 approximately between the parts 36 and 37 two elastic straps 41, whose opposite extremities extend downwardly into the pocket 35 where they are secured as shown at 42. These straps serve to draw the entire boot into the pocket when the various parts of the boot 55 and the straps are released, as hereinafter explained, preparatory to the elevation of the top to the position shown in Fig. 1. To the part 37 are applied elastic straps 43 which are secured to the part 37 at the opposite ends of the strap as shown at 44 and 45. Normally these straps collapse the part 37 into relatively small compass in a manner that will be readily understood, the material of the part 37 between the points of attachment 44 and 45 being free from the straps.

Hence, when the latter are in their normal position they reduce the width or length of the part 37 in the manner required in order to facilitate its entrance into the pocket 35. There are two parts 39, each of which is secured to the part 37 as shown at 46, the free ends of the parts being provided with eyes 47. There are two parts 38 which when the boot is spread out are placed in the position shown in Fig. 6, extending laterally from the part 36 and are arranged to be collapsed by elastic straps 49 which are connected with the parts 38, as shown at 50. These elastic straps 49 are in reality a continuation of a relatively long elastic strap 51 which extends through a pocket 52 formed in the part 36. Normally this elastic strap construction 49 and 51, holds the parts 38 in the collapsed position, whereby they are caused to overlap the part 36 in order to facilitate the movement of the entire boot into the pocket 35. Other straps 53 are connected with the part 36, as shown at 54.

After the top of the machine is lowered or moved to the position shown in Fig. 8, the boot which at this time is entirely collapsed within the pocket 35, is pulled out of the pocket, whereby the part 36 takes the position indicated in Fig. 8 and covers the top portion of the rear part of the top, while the part 37 engages the rear part of the top, as indicated in Fig. 8 and also extends underneath the top, after which the elastic straps 43 are connected through the medium of their eyes 55 with the lower extremities of pins 56 which pass through perforations 57 formed in parts 58, forming the lower portions of brackets 59 which are secured to the sides of the body of the machine by means of horizontally disposed projections 60, which are expanded into plates 61, the latter being secured to the body 5 of the machine by means of suitable fastening devices 62. The part 58 projects rearwardly from the bracket 59 and forms a stop for the lower extremity of a spiral spring 63 whose upper extremity engages a tension nut 64 threaded on an actuating rod 65 upon which the pin 56 is formed. In other words, the pin 56 is simply the reduced lower end of the rod 65, the reduction in diameter being made in order to facilitate the attachment of certain parts, as herein-after more fully explained. The part 57 forms a guide as well as a support for the rod 65, the upper extremity of the latter being pivotally connected, as shown at 66, with the base 67 of a hook 68, the latter being pivotally connected, as shown at 69 with the upper extremity of the bracket 59. When the top is down the hook 68 is thrown into engagement with one of the side arms 70 of the forward top part, a lever 72 of the top being below the part 70, while the bows 8 and 7 are next below in the order named, 130

the bow 7 engaging a seat 73 mounted on a projection 74 carried by the bracket 59. In other words, when the top is in the down position, as shown at Fig. 8, the parts 70, 72, 8 and 7 are arranged approximately as shown in Fig. 3, so that when the hooks 68 on opposite sides of the structure are in the retaining position shown in Fig. 3, the top is securely held in the down position and the pins 56 of the rod 65 extend below the part 57, the hook 68 being locked in the down position by the pawl extremity 75 of a rod 76, whose opposite extremity 77 constitutes a latch bolt adapted to engage a stem 79 just below a recess 78, the stem being slidably mounted in a keeper 80 supported on the inner end of an arm 81 carried by the bracket 59 and formed integral with the top of the latter. This stem 79 is normally held in the position shown in Fig. 5 by a spiral spring 181 which surrounds the stem above the part 80 which is engaged by the lower extremity of the spring whose upper extremity engages the enlarged top 82 which forms a shoulder. Hence, when the stem, there being one on each side of the machine, is in the uppermost position, the pawl extremity of the rod 76 engages the hook 68 to lock the latter in the top retaining position when the latter is down, but when the stems 79 are moved downwardly sufficiently to allow the latch bolt extremity 77 of the rod 76 to enter the recesses 78 of the stem, the pawl extremity 75 will be disengaged from the recesses in the base of the hook 68, and the rod 65 acting under the influence of the spring 63 which is under tension when the hook is in the full line position in Fig. 3, will act to throw the hook 68 from the full line position in Fig. 3 to the dotted line position in the same figure, whereby the top will be released and allowed to move into the raised position by virtue of the recoil of the two sets of spiral springs 31 which are held under tension when the top is down, as heretofore explained.

Referring now again to the arrangement of the boot when it is removed from the pocket 35 in order to cover the top when in the collapsed position, shown in Fig. 8, when first adjusted the eye extremities 83 of the elastic strap extensions 49 will be first connected with the projecting extremities of the pins 56 of the rods 65. This operation will draw the parts 38 of the boot downwardly from the top part 36 covering the sides of the collapsed top of the automobile. The eye extremities 47 of the parts 39 will then be connected with the pins 56 below the eyes 83. The elastic straps 43 will then be extended to cause the part 37 of the boot to cover the automobile top underneath, whereby the said part will be stretched smooth or taut for the purpose, after which the eyes 55 will be connected with the pins 56 below the

eyes 47, and finally the straps 53 will be carried downwardly and their eye extremities connected with the pins 56 below the eyes 55.

The boot will then be secured in its exposed position in order to perform its function of covering the automobile top when in the down position.

Before the top can be released preparatory to being raised, it is necessary that the pawl extremity 75 of each rod 76 shall be disengaged from its recesses in the base 67 of the hook 68, but the movement of the rod 76 for this purpose cannot occur until the pins 79 are depressed sufficiently to bring their recesses 78 into line with the latch bolt extremities 77 of the rods 76. Connected with eyes 84 with which the lower extremities of the stems 79 are provided, are wires or other suitable devices 85 which extend downwardly into the lower part of the pocket 35 below the portion thereof which the boot 34 occupies when collapsed, the lower ends of these wires (see Figs. 1 and 4) being connected, as shown at 86, with arms 87 of bell crank levers 88 which are fulcrumed as shown at 89, upon a stationary member 90, which is supported in the lower part of the pocket by means of rods 91 which are secured to the member 90 by means of staples 92, or other suitable fastening devices. The lower extremities of these rods pass through bottom plates 93, while their upper extremities 94 enter openings in the back of the body of the machine, these extremities being curved for the purpose. Other arms 95 of the bell crank levers 88 are connected by a rod 96 which in turn is provided with a projection 97 which passes through a slot 98 formed in the upturned end 99 of the core or movable part 100 of the solenoid 101 whose coil is in a circuit, the conductors 102 and 103 of which are connected with a suitable source of current, the arrangement being such that when a push button 104 is pressed, the circuit is closed and the solenoid energized, with the result that the rods 96 together with the levers 88 and the wires 85 are moved to the dotted line position in Fig. 4, moving the stems 79 sufficiently to allow the latch bolts 77 of the rods 76 to enter the recesses 78 of the said stems, the rods 76 being under tension to assume such position through the medium of springs 105 which are connected at one end, as shown at 106, with the pawl extremity 75 of the rod 76, the opposite extremity of this spring being connected as shown at 107 with the central top portion of a channel member 108 which is pivotally connected with the top of the bracket 59, its pivotal axis being the same as that of the hook 68, the base of the latter being pivotally connected with the bracket, as shown at 69. As soon as this occurs the

pawl extremity 75 of the rod 76 will be disengaged from its recess in the base 67 of the hook 68 and the rod 65 acting under the recoil of its spring 63, will move upwardly 5 to the dotted line position in Fig. 3, and throw the hook 68 to the dotted line position in the same figure. This upward movement of the rod also carries the pin extremity 56 of the rod upwardly far enough to release 10 the boot parts 39, the straps 43 and the straps 53, in which event the strap parts 49 together with the strap member 51 will serve to draw the side parts 38 of the boot inwardly, while the elastic straps 43 will collapse the part 37, and the elastic straps 41 will draw the entire boot structure downwardly 15 into the pocket 35 in which the boot is concealed when not in use. This will happen immediately after the aforesaid parts are 20 disengaged from the pins 56, and as the automobile top has been released by the movement of the hook 68 to the dotted line position in Fig. 3, the recoil of the two sets of springs 31, acting on the crank arms 24, 25 will actuate the rock shaft 23, whereby the crank arms 21 are operated to raise the top in the position shown in Fig. 1, through the medium of the links 19 and the crank arm 17. Now, when it is desired to lower the 30 top to the position shown in Figs. 3 and 8, this may be manually accomplished, and as soon as the top is lowered, the two channel members 108, there being one on each side of the machine, are raised to the dotted line 35 position in Fig. 3, these channel members being each provided with a hand piece 109 for the purpose. This movement of the channel members to the dotted line position in Fig. 3 first acts on the hooks 68 which 40 lie in the path of said members to throw the hooks into the top engaging position, shown in full lines in Fig. 3. As soon as this is done, the recesses in the base 67 of the hooks are brought into line to be engaged by the 45 pawl extremities 81 of the rods 76, and the pawl extremities are moved into said recesses by the action of the springs 105 which are placed under tension to perform this function when the said channel members are 50 moved into the dotted line position. This movement of the pawl extremities 75 actuates the rods 76 to disengage the latch bolt extremities 77 from the recesses 78 of the stems 79, allowing the stems to move upwardly 55 in response to the recoil of the springs 81. The channel members may then be returned to their normal position, and when this is done the springs 105 will be under tension to disengage the pawl extremities 75 from the parts 67 of the retaining hooks; but this cannot occur since the latch bolt extremities 77 cannot enter the recesses 78 of the stems. It will be understood that the channel members 108 are 60 so pivoted with reference to the points 65

where the springs 105, are connected with the pawl extremities of the rods 76 that the aforesaid result will follow. In other words, while the tension of the springs 105, when the channel members 108 are in the full 70 line position in Fig. 3, acts on the rods 76 to hold their latch bolt extremities in the recesses 78 of the stems 79, the action of the tension of these springs is in the opposite direction when the channel members are 75 thrown to the dotted line position in Fig. 3, and consequently, serves to move the rods 76 in the opposite direction, which is necessary in order to secure the retaining hooks in the position to lock the top in its lowered 80 position.

It should be explained that in the event that the solenoid 101 should not work, as if the circuit were broken or the battery too weak for the purpose, the same result may 85 be manually accomplished by pushing downwardly on the top 82 of the stems 79 until the recesses 78 are thrown into position to be engaged by the extremities 77 of the rods 76.

Having thus described my invention, what I claim is:

1. The combination with a collapsible vehicle top, of spring-actuated means for raising said top, means for holding the top 95 in the collapsed position against the tension of the spring-actuated means, means for locking the holding means against movement, means for releasing the locking means, and positively operating means for moving the holding means into inoperative position after release of the locking means.

2. The combination with a collapsible vehicle top, of spring-actuated means for raising the said top, means for holding the top 105 in the collapsed position against the tension of the spring-actuated means, means for locking the holding means against movement, means for releasing the locking means, and spring-actuated means for moving the holding means into the inactive position after the release of the locking means.

3. The combination with a collapsible vehicle top, of spring-actuated means for raising the said top, means for holding the top 115 in the collapsed position against the tension of the spring-actuated means, means for locking the holding means against movement, means for releasing the locking means, spring-actuated means for moving the holding means into the inactive position after the release of the locking means, a collapsible boot connected with the machine and normally yieldingly retained in the collapsed position, the said boot having parts 120 connected with the last named spring-actuated means when the boot is expanded, to hold the boot into position to perform its top covering function, said parts being arranged to be released when the last named 130

spring-actuated means moves in the performance of its function.

4. The combination with the collapsible top of an automobile or other vehicle, the latter having a pocket in its rear portion, a collapsible boot normally yieldingly retained in the said pocket, means for holding the boot in the expanded position to cover the automobile top when the latter is in the down position, said last named means being movable to release the boot and allow the latter to return to its normal position within the pocket.

5. The combination with the collapsible top of an automobile or other vehicle, the latter having a pocket in its rear portion, a collapsible boot normally yieldingly retained in the said pocket, means for holding the boot in the expanded position to cover the automobile top when the latter is in the down position, said last named means being movable to release the boot and allow the latter to return to its normal position within the pocket, means for holding the top in the collapsed position, means for locking the holding means against movement, and means for releasing the locking means, the boot holding means being connected to automatically disengage the top holding means when the latter is unlocked, this function being accomplished during the movement of the boot holding means to release the boot as aforesaid.

6. The combination with a collapsible top for automobiles and other vehicles, the vehicle having a pocket in its rear part, a collapsible boot normally yieldingly retained in the collapsed position within said pocket, a pivoted dog for holding the top in the down or collapsed position, means for locking said dog in the holding position, means for releasing the locking means, a spring-actuated rod normally under tension to move the said dog to disengage it from the top holding position when the dog is released, the boot having parts which when it is expanded to perform the top covering function are connected with the spring-actuated rod, said parts being arranged to be released when said rod moves to disengage the said dog, and means for automatically raising the top when the dog is released, whereby the top raising function is performed as soon as the boot is released and allowed to return to the said pocket.

7. The combination with a collapsible top for automobiles or other vehicles, of a pivoted dog for holding the top in the down or collapsed position, means for locking the dog in the holding position, means for releasing the locking means, a spring-actuated rod normally under tension to move the said dog to disengage it from the top holding position, and means for automatically raising the top when the said dog is disengaged.

8. The combination with a collapsible top for automobiles or other vehicles, of a pivoted dog for holding the top in the down or collapsed position, means for locking said dog in the holding position, means for releasing the locking means, a spring-actuated rod normally under tension to move the said dog to disengage it from the top holding position, and spring-actuated means for automatically raising the top when the dog is released.

9. The combination with a collapsible top for automobiles and other vehicles, the vehicle having a pocket in its rear portion, a boot normally yieldingly retained in the collapsed position within said pocket, a spring-actuated rod, means for locking said rod against movement in response to the tension of its spring, means for releasing the locking means, the boot having parts which when it is expanded to perform the top covering function, are connected with the said rod to maintain the boot in the top covering position, the arrangement being such that the movement of the rod when released, releases the boot and allows the latter to return to the said pocket.

10. The combination with the collapsible top of an automobile or other vehicle, of a pivoted dog for holding the top in the collapsed position, a rod having a pawl at one end adapted to enter a recess in the dog to lock the latter in the top holding position, the other end of the rod being formed into a bolt, a latch stem having a socket to receive said bolt, the stem being normally spring-actuated to hold the socket out of alignment with the bolt end of the rod, a spring connected with the rod to place stress thereon to move its bolt extremity to engage the socket when the stem is moved against the tension of its own spring to bring the socket into proper position, the arrangement being such that the movement of the rod to cause its bolt end to enter the socket of the stem, disengages the pawl from the dog.

11. The combination with the collapsible top of an automobile or other vehicle, of a pivoted dog for holding the top in the collapsed position, a rod having a pawl at one end adapted to enter a recess in the dog to lock the latter in the top holding position, the other end of the rod being formed into a bolt, a latch stem having a socket to receive said bolt, the stem being normally spring-actuated to hold the socket out of alignment with the bolt end of the rod, a spring connected with the rod to place stress thereon to move its bolt extremity to engage the socket when the stem is moved against the tension of its own spring to bring the socket into proper position, the arrangement being such that the movement of the rod to cause its bolt end to enter the socket of the

stem, disengages the pawl from the dog, a pivoted arm with which the rod spring is connected, said arm being movable to reverse the direction of the stress on the rod due to the spring to cause the bolt extremity to disengage itself from the socket of the stem and the pawl extremity to engage the dog in locking relation when the dog is

moved to the top holding position, the dog when disengaged from the top lying in the path of said arm when such movement is imparted to the latter, whereby the dog is moved into the top locking position.

In testimony whereof I affix my signature.

HARRY W. McMULLIN.
